UNITED STATES PATENT OFFICE.

JULIUS DANQUIGNEY, OF LINDENHURST, NEW YORK, ASSIGNOR TO MAURICE LEVY COMPANY, INC., A CORPORATION OF NEW YORK.

POWDER-PUFF MAKING.

Application filed August 30, 1924. Serial No. 735,113.

To all whom it may concern:

Be it known that I, JULIUS DANQUIGNEY, a citizen of the United States, residing at Lindenhurst, Long Island, in the county of 5 Suffolk and State of New York, have invented certain new and useful Improvements in Powder-Puff Making, of which the following is a specification.

This invention relates to the making of 10 powder puffs, and more particularly to a novel process for that purpose whereby a very considerable saving in labor is effected.

Among the objects of this invention is to provide a process for the making of powder 15 puffs whereby the same may be completely sewn in one operation, thus eliminating the finishing necessary after the powder puff in usual course of manufacture has been turned inside out.

20 In the present state of the art powder puffs are made by placing two pieces of velvet or other suitable material with their nap portions in contact or face to face, sewing both pieces around in an arc by machine and leaving a gap between the ends of the stitched line thus forming a pocket 25 adapted to be turned inside out through said gap so as to bring the nap of the velvet upon the outside of the powder puff in the usual manner while at the same time concealing the stitches and the unfinished edges 30 of the velvet within the powder puff itself. The gap or opening aforesaid is then sewn up preferably by hand whereby it is difficult 35 or tedious if not impossible to so form the stitches as to cause the same to be hidden within the powder puff and between the folds thereof to secure a uniformity of appearance of said powder puff. My invention 40 eliminates this finishing or second sewing operation whether done by hand or by machine.

Other objects, therefore, of my invention are to provide a process wherein the cost of 45 manufacture generally is greatly reduced, and whereby a powder puff of more uniform and pleasing appearance is secured.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to

the accompanying drawings in which like reference characters designate the same parts in the several views, and in which—

Figure 1 is an elevation showing an initial step in securing the objects aforesaid. 60

Fig. 2 shows the next step in forming powder puffs by my improved process which consists in severing the group structure into units.

Fig. 3 shows a modification of Fig. 2 or 65 another way of securing the objects aforesaid.

Fig. 4 is an end view showing the powder puff in course of being turned inside out.

Fig. 5 shows the next finishing step. 70

Fig. 6 shows a completed powder puff.

Figs. 7 and 8 show diagrammatic views of a machine for stitching the powder puffs as shown in Fig. 1.

Fig. 9 is a view of a needle used in said 75 machine.

Referring now more specifically to the drawings, 10 and 10^a represent strips or the like of velvet or other suitable material lying with their nap or pile portions in contact or face to face. These strips are mounted or held in any suitable manner so as to be secured against movement relatively to each other while a thread 11 is used to sew said strips together at any portion 80 thereof and in a circular path or the like as an initial step in the formation of the powder puff. The stitch used is of the general type which permits the thread to be drawn through the fabric as against the 85 usual interlocking stitch which does not permit the thread to be drawn through the fabric without destroying the stitch itself. I have found that the preferred stitch is, for the sake of cheapness and simplicity, 90 preferably of the basting type. Thus beginning at 12 and advancing in the direction of the arrow one comes back again to the starting point. In the preferred method of using my invention the stitching line is re- 100

inforced at 12 to prevent opening up or looseness thereof as by means of one or more extra stitches 13 or the like, a looseness being permitted in the thread at some point or points along the stitched line spaced 105 from 12. This looseness or excess of thread takes the form of a loop or free portion 14 shown as being formed wholly at one place and only upon the side of the fabric 10. Or in like manner a plurality of loops 110

14^a may be formed, of substantially the same size or varying in size for a purpose to be soon set forth. These loops are turned to lie upon the fabric and preferably within 5 the line of stitching so as to preclude the possibility of severing the same when the fabrics are severed as at 15 to form unitary structures for the individual powder puffs. The looseness in the thread as aforesaid 10 combined with the adaptability of the stitch for permitting the thread to be drawn through the fabric allows the operator to readily draw the pieces of fabric or disks 16 and 17 apart at the region of the looseness 15 of the thread to form an opening or gap by grasping a portion 19 of the disks remote from said opening and drawing the same through so as to reverse the pieces of fabric and cause their nap surfaces to be on the 20 outside of the article, all possibility of any stitches coming loose or opening up being precluded since the thread is continuous all along. If the modification shown in 25 Fig. 3 is used the spreading apart and formation of this opening 18 is accomplished more rapidly.

The operator then draws up the thread to take out the slack in the stitching and bring said disks against each other through- 30 out the periphery thereby again forming a loop at a convenient point, said loop being then severed, and the powder puff will then appear substantially as shown in Fig. 5 with the loose ends 11^a and 11^b of the thread 35 projecting from between the folded edges of the disk. The ends are then secured in any suitable manner or tied into a knot 20. This knot becomes drawn into the stitching line and is thus concealed within 40 the powder puff.

This process is not confined to any specific machine or device or manner of manufacturing, but is capable of various modifications to suit the needs of different manufacturers 45 and the requirements of the market as the same vary from time to time. This process lends itself among other things to hand-sewing and the like, though for maximum economy and advantage, the process should 50 be used in connection with a machine which may be of the type shown herein or of any other suitable type.

For this purpose it will be observed that 21 is the frame of a machine having a bed 55 or support comprising rollers 22 upon which are tightly mounted fabrics 10 and 10^a in the manner and for the purpose disclosed in connection with Fig. 1. Beds or supports 23 and 23^a are supported upon the 60 rollers 24 which run upon tracks 25 formed upon said frame. These bed frames are thus adapted to reciprocate along a fixed path toward and away from said fabrics. Mounted upon the bed frames are clutches 65 26 and 26^a which are adapted to be

moved into close proximity to said fabrics, the clutches upon the different sides thereof being in alignment so as to be adapted in turn to grasp a needle 27 having a central eye 28 in order to draw the 70 thread 11 through the fabrics in one direction or in another. The bed comprising said rollers 22 is movable in a plane at right angles to said path of movement of said bed frames 23 and 23^a. Fig. 8 shows the stitching in process of formation in the direction of the arrow *a*, this being accomplished by causing the entire fabric to move in the other direction and in a direction determined by the radius of the line of stitching. The arrow *b* shows the path through which the fabric must move intermittently to complete the stitching, a small angular movement occurring before the formation of each stitch. More specifically, after the bed frame 23 has brought the clutches 26 up to the fabric so as to pass the needle therethrough, the clutches 26^a are brought against the fabric and the machine is operated to cause the latter clutches to 80 grip the projecting portions of the needles, while the clutches 26 release their hold upon the other end portions of the needles, the bed frame 23^a being then caused to move away from the fabric thereby causing the threads to be drawn through the same. When this is done frame 23^a is moved back again toward the fabric, which in the meantime is moved as indicated by the arrow *b* into position for the next stitch, the needle and thread being then passed therethrough in reverse directions, and so on until the stitching is completed.

Fig. 7 shows a loop or free portion 14 in process of being formed, this being accomplished by stopping the bed frame 23, which is on the opposite side of the fabric relatively to said loop, before the thread 11 has been drawn all the way through the fabric. To effectively accomplish this purpose, an attachment is provided which may be operated in any suitable manner to limit the motion of said bed frame in any predetermined position as shown in Fig. 7 instead of to the furthest position indicated in dot-dashlines at 24^a, in which latter case no loop would be formed but the thread would be drawn taut against the fabric. For this purpose a catch or stop lever 29 is shown pivoted at 30, said lever having an arm or head 31 which is normally kept in spaced relation to said bed frame in any suitable manner as by a spring 32 or the like, said lever being operative as by a lever 33 joined thereto by a connecting rod 34, the last-mentioned lever being operated automatically or manually as at 35. As shown in the figure, 35 being depressed by the operator, the head 31 is lowered against the force of the spring 32 to lie in the path of the bed frame 23^a as 100 105 110 115 120 125 130

the same recedes from the fabric, and thereby to limit the outward movement thereof relatively to said fabric and so to prevent the thread 11 from being drawn entirely 5 through, thus leaving a loop 14. For the formation of the modification shown in Fig. 3 an attachment of a different specific type, but one which is substantially the same in principle, can be employed, said attachment 10 being preferably operated automatically. The machine before described, including the needle illustrated in Fig. 9, are well known and have been used for many years in embroidering various fabrics, and hence a more 15 detailed explanation thereof is not necessary to fully instruct persons skilled in the art.

The severing of the fabric into individual powder puffs is accomplished upon any suitable machine, and likewise all subsequent 20 operations may be so accomplished.

My invention is to be understood as embracing all modifications that may be made wherein a loose thread or a thread having a loose or free portion or portions in combination with a stitch which permits the thread to be moved or drawn in any way through the fabric may be used. Nor is my invention to be limited as to the location or form of said loose or free portion of the 30 thread or the type of stitch used, or the kind or form of powder puff whereon it is used or other device made up of two similarly formed pieces of fabric stitched together along their margins and subsequently turned. 35 Variations of form and process will be evident to those skilled in the art, and the modifications disclosed herein embody the most perfect form of my invention now known to me.

40 I claim:

1. As an article of manufacture, a powder puff comprising two pieces of fabric, each said piece of fabric having a nap surface and the said nap surfaces being on the outside 45 of the said article, the edges of the said pieces of fabrics being inturned and being

continuously connected by a continuous piece of thread passing through said inturned edges at a plurality of spaced points and forming loop portions intermediate said 50 spaced points, the said thread being movable with respect to the said pieces of fabric at the said spaced points, the said thread being drawn tight and having uniform tension throughout, and being retained against 55 release so that the sole connection between said pieces of fabric consists of a single piece of thread under uniform tension.

2. An article of manufacture according to claim 1 in which the said thread is severed 60 at one point thereof and in which the severed ends are held to each other against release.

3. A method of making a powder puff which consists in forming stitches by passing a thread through spaced points of two pieces 65 of fabric having nap surfaces while the said nap surfaces are held adjacent each other and without interlocking the consecutive loops of thread thus formed so that the said thread can be moved relatively to the said 70 pieces of fabric, connecting the thread portions at the end and at the beginning of the said line of stitches to each other so as to form a continuous and connected line of 75 stitches, reversing the said pieces of fabric at one of the said loops of the thread spaced from the point where the beginning and the end of the said line of stitches are connected to each other, pulling the said thread tight so as to tightly connect the said two pieces 80 of fabric to each other, and then holding the said thread in position so as to prevent the release of the said pieces of fabric.

4. A method according to claim 3 in which the loop of thread at the point where the 85 said pieces of fabric are reversed is severed before the said thread is drawn tight, and in which the severed ends of the thread are knotted to each other to retain the thread in the tight position.

In testimony whereof I affix my signature.
JULIUS DANQUIGNEY.
